WASHING MACHINE

Robert J. Waterworth, Sidney, Ohio, assignor to
Prima Manufacturing Company, Inc., Sidney,
Ohio, a corporation of Ohio

Application June 27, 1932, Serial No. 619,433

2 Claims. (Cl. 210—75)

This invention relates to improvements in washing machines, and has for its object to provide, in connection with a washing machine, an improved means for driving the spinner or extractor, together with means for resiliently and yieldingly mounting the extractor tank so that during the operation of the washing machine it will not creep about on the floor or supporting surface.

10 It is also an object of this invention to provide as part of a spinner or extractor unit, an extractor basket which has therein a perforated lining, spaced from the walls of the basket and supported in this condition by the basket.

15 It is particularly the object of this invention to provide, in connection with the spinner or extractor unit, a basket having a strainer lining supported at its upper edge by the edge of the basket, and attached to the basket at its lower edge at a plurality of spaced points.

20 It is also an object of this invention to provide, in connection with a washing machine, a motor for operating the moving parts of the machine, and a simple and efficient means for supporting the motor from the chassis of the machine.

25 It is also an object of this invention to provide, in connection with the shafts, bearings that have associated with them oil chambers formed by the bearings, the bearings consisting of an outer rigid member and an inner porous member.

30 It is a further object of this invention to provide, in connection with the washing machine having a tub with a shoulder therein and an extractor unit, means for withdrawing the water from the extractor unit and conveying it to the tub and for draining the water from the tub, and also from the extractor unit.

35 These and other advantages and objects will appear from the following description taken in connection with the drawings.

40 Referring to the drawings:

Figure 1 is a vertical section through the washing machine showing the operating mechanism for oscillating the oscillator and rotating the spinner basket.

45 Figure 2 is a bottom plan view with the gear case housing removed.

Figure 3 is a vertical section through the dolly and the dolly standard.

50 Figure 4 is a vertical section through the spinner unit showing the mechanism by which the basket is rotated, and means for clutching and unclutching the basket.

55 Figure 5 is a section on the line 5—5 of Figure 4.

The present washing machine has a chassis or base composed of a base plate or support member 1, having a peripheral downwardly extending flange 2. This base with its flange are supported by legs 3, each of which has on its lower end a 5 caster 4. These legs are braced by means of a brace 5. The base plate or support is in the form of a sheet metal table, which supports at one end a tub 6.

Extending through the bottom of the tub and 10 the base plate or chassis is a hole 7. Supported on the bottom of the tub is a stem or standard 8, which has at its bottom an outwardly extending circular flange 9 resting upon the bottom of the tub and attached to the bottom of the tub and 15 the base plate by means of screws 10. Located around the standard about midway between the flange 9 and the top of the standard is a shoulder 11, which supports a lower agitator bearing 12, composed of some suitable fibrous material. Ad- 20 jacent the upper end of the standard is a second agitator bearing 13, composed of the same or similar material.

Extending through the bearing 13 and through the wall of the standard are pins 14 for holding 25 the bearing on the standard. Engaging the lower edge of the upper agitator bearing is a pilot screw 15, which passes through one part of a dolly 26.

Resting on top of the standard is an agitator supporting washer 16, which has resting thereon 30 the bottom of a lower clutch 17, held by a pin 18 through the upper end of a shaft 19. Cooperating with the lower clutch member is an upper clutch member 20, which has a shoulder 21 thereon adapted to engage the under side of a shoulder 35 22 on the dolly. This upper clutch member is cup-shaped, and has through its upper end, which is square, a hole 22. This hole has in one end a ball 23, against which one end of a spring 24 engages. The other end of this spring 24 en- 40 gages a screw 25 threaded into the other end of the hole.

Fitting over the upper end of the upper clutch member and over the upper end of the dolly is a clutch cap 26, held on the clutch member by 45 means of a screw 27. In the upper end of the upper clutch member is an annular hole, which seats a spring 27a between the bottom of the hole and the clutch cap.

The agitator or dolly 28, which is bell-shaped, 50 fits over the top of the standard, and the shaft located in the standard is supported on the upper end of the clutch member and has thereon, on the inside, a shoulder 29 adapted to be engaged by the shoulder 21 to limit the upward 55

movement of the upper clutch member. This dolly or agitator is supported on the supporting washer 16 by means of a shoulder 20, located on the inside of the dolly or agitator, below the 5 shoulder 29.

In the upper end of the dolly is a notch 31, and below this notch is a hole 32. When the upper clutch member is out of engagement with the lower clutch member the ball 23 projects into the notch 31 and tends to hold the cap in position such as that shown in Figure 3. When the upper clutch member is in engagement with the lower clutch member the ball 23 partly projects into the hole 32 so that the clutch members are held in engagement with one another for operating the dolly through the operation of the shaft. This ball has a snap action between the notch 31 and the hole 32. The clutch mechanism is operated by an upward or downward movement of the clutch cap 26.

The lower end of the dolly is bell-shaped, as indicated by the numeral 33, and has on its lower end a downwardly extending circular flange 34. Extending radially outwardly from the dolly or agitator is a plurality of vanes 35, each of which has on its periphery a bead 36.

Between the standard and shaft adjacent the bearing 13 is an inner bearing 37, which has holes 38 therein adjacent the pins 14 for holding a lubricant. Immediately above the bearing 13 and below the supporting washer 16 is a cavity or chamber 38a adapted to contain a lubricant. In fact, all of the space from the lower bearing to the clutch members may be filled with a lubricant. The bearings are formed of a fibrous material that will absorb and hold the lubricant so that frequent lubrication is unnecessary.

Immediately below the standard and supported on the base beneath the standard, and attached to the base by means of the screws 40, is a housing 39. In fact, these screws pass through the flange 9, the bottom of the tub and the base plate into a flange on the upper periphery of the housing. The base plate has attached thereto a plate 40 by means of supporting bolts 41. Substantially in the center of this plate 40 is an upwardly extending boss 42, which has a circular hole therethrough for receiving a bearing 43. This bearing is composed of the same fibrous material that is used in connection with the other bearings. This bearing serves as a bearing for the lower end of the shaft 19.

There is also on this plate 40 a boss 44, which has an opening therein to receive one end of a bolt 45, the other end of which bolt supports a rotating gear 46. Adjacent one end of this plate there is another boss 47, through which passes a shaft 48 surrounded by a bearing 49 of fibrous material. Cooperating with the bearing 49 for supporting the shaft 48 is another boss 50, which has a bearing 53, located in a gear case 51 attached to the plate 40 by means of screws 52.

On the upper end of the shaft 48 is a pulley 54 adapted to operate the gear mechanism located within the gear case, and to oscillate the shaft 19 and the dolly carried thereby. The lower end of the shaft 48 is located in the bearing 53. Intermediate the bearing 53 and the bearing 49, on the shaft 48, is a pinion 55 which engages or meshes with the gear 46. On the end of the plate 40 opposite the boss 47 is a boss 56, which has mounted therein a shaft 57, to which a quadrant 58 is attached.

This quadrant engages a small gear or pinion 59 located on the lower end of the shaft 18,

below the bearing 43. When this quadrant oscillates it causes the shaft 18 to oscillate through the pinion 59. Extending from a pin 61 on the quadrant to a pin 62 on the gear 46, is a link 60. By means of this link the rotation of the gear 46 will transmit to the quadrant an oscillating movement, which also conveys to the shaft 18, through the pinion 59, an oscillating movement.

Located on the shaft 18 and substantially even with the flange 9, is a deflector 63. The periphery of the tub is lower than the center and has therein, at one point, a circular depression 64 with a hole in the bottom of the depression. Engaging the under side of the depressed part of the bottom is an elbow or spout 65. The upper end of this spout, which engages the depressed part of the bottom, is shaped or flanged out to conform to the shape of the bottom of the tub around the hole, as indicated by the numeral 66.

For clamping the drain spout or elbow to the bottom of the tub there is provided a strainer 67, which is threaded into the upper end of the spout or elbow adjacent the flanges 66. There is also provided in this strainer a screw 68 for engaging a certain part of the elbow or spout for holding the strainer in position. In one end of the elbow or spout is a plug 69, through which a screw shaft 70 extends. On the inside end of this screw shaft is a valve 71, adapted to close the spout to prevent water passing from the tub out through the spout.

This spout has two openings or arms, one 72 extending downwardly and closed when not in use by means of a cap 73, threaded on the open end thereof. The other branch 74 extends horizontally from the spout from a point opposite where the arm 72 extends. These arms so extend from the spout that when the valve is closed no water can get from the tub into either of them, but when the valve is open the water in the tub may pass 40 into either arm. If the cap 73 is off the water will pass out at the arm 72.

This branch 74 is connected by means of a hose 75 to a pump 76, which is supported by means of a bracket 76a attached to the flange at one side 45 of the base or chassis. This pump is composed of a casing which has two inlet pipes, one 77 to which one end of the hose 75 is attached, and the other 80. The pump has one outlet pipe 78, to which one end of a hose 79 it attached. This hose has on 50 its other end a goose neck 79a to hook over the upper edge of the tub through which water may be pumped into the tub from some other part of the washing machine.

The inlet pipe 80 is connected to a pipe or elbow 81 by means of a hose coupling 82. This elbow 81 is similar in all respects to elbow 65 except that it has no branches. It is supported in the bottom of a tank 83 in the same manner that the elbow 65 is supported in the bottom of the tub. This tank 83 is a spinner tank and is located on top of the chassis or support. Between the bottom of the tank and the adjacent part of the chassis or support is a gasket 84 composed 65 of some suitable resilient material. This tank is attached to the tub by some resilient means 84, as shown in Figure 1.

Extending up through a hole in the base or chassis and through a hole in the center of the bottom of the tank, is a cylindrical spinner mount 85. This spinner mount has a vertically extending circular opening therein, the purpose of which will be later described. At the lower end of this spinner mount is an outwardly extending circular 75

flange 86, which engages the under surface of the chassis or support 1.

Extending outwardly and downwardly from one side of the flange 86 is an arm 87. Between 5 the chassis or support and the bottom of the tub is the gasket 88. Above the bottom of the tub and around the cylindrical spinner mount is a similarly composed gasket 89. For the purpose of holding these gaskets and the support and the 10 bottom of the tank in close fitting engagement with each other there is provided on the spinner mount a nut 90. This nut is threaded against the upper gasket and presses the gaskets and the bottom of the tub on the support.

15 Within the spinner mount is a porous bearing 91, which forms with the mount an oil chamber 109. Extending up through this bearing and supported thereby is a shaft 92. This shaft has on its lower end a collar 93. Above the collar 93 is a 20 clutch sleeve 94, which is loosely mounted upon the shaft for vertical movement by means of a Woodruff or other suitable key 95. By means of this key the shaft and sleeve rotate together, but the sleeve may move longitudinally of the shaft. 25 Between the sleeve and the collar 93 is a spring 96, tending to force the sleeve upward.

Attached to the lower end of the clutch sleeve 94 is a fork plate 97, which has thereon a lower fork disc 98 and an upper fork disc 99. The upper 30 end of the clutch sleeve is formed into a clutch plate 100, which has mounted thereon a clutch disc 102. The clutch sleeve immediately adjacent the clutch plate 100 is hollowed out and has therein, around the shaft, a collar 101.

35 This collar serves to support and prevent the downward movement of a pulley 103, freely rotatable on the shaft 92. This pulley is prevented from moving upwardly on the shaft 92 by means of a collar 104. This pulley is provided adjacent 40 the shaft with a porous bearing 103b, which forms with the pulley one wall of an oil chamber 103a. This oil chamber is formed in the interior of the pulley 103, around the bearing 103b.

45 Located somewhat spaced from the upper end of the bearing 91 is a fourth collar 106, between which and the upper end of the bearing 91 is a thrust bearing 105. The upper end of the shaft 92 has a notch 107 therein, the purpose of which will be later described. The upper part of the 50 cylindrical spinner mount is hollow and provides an oil seal space 108. An oil chamber 109 is formed between the cylindrical spinner mount and the bearing 91.

55 One of the novel features of this invention is the basket, which is composed of three parts, the basket bottom 110, which has extending upwardly from the center thereof a cap 111 adapted to fit over the upper end of the shaft 92 and the upper end of the cylindrical spinner mount 86. The 60 upper end of this cap has a pin 112 which fits in the notch 107 so that when the shaft 92 rotates the basket will rotate with it. The upper part of the spinner mount forms with the cap a lubricant chamber, such as 108a.

65 Around the periphery of the bottom of the basket is a plurality of holes 113, through which the water may pass into the tank. Another part of the spinner unit is the side walls 114 of the basket, attached to the bottom of the basket by 70 means of rivets 114a. The upper edge of the basket is turned over and inwardly at 115 and forms an upper support for the third part of the spinner unit, which is a screen 116. This screen is of the same general shape but of less diameter 75 than the basket, both of which taper inwardly

from the bottom toward the top so each is more or less in the shape of a truncated cone. The upper edge of the screen is supported by the inturned upper edge of the basket.

The lower edge of the screen has around it a 5 clamping member 117. This clamping member is circular in shape and conforms to the size of the larger part of the screen, and is slightly less in diameter than the diameter of the basket at the point of the basket adjacent this clamp. The 10 lower end of the screen is attached to the walls of the basket at four points by means of rivets 118.

Since the diameter of this clamp, which is normally circular in shape, is less than the diameter 15 of the basket, these rivets tend to pull the part 117 out of its circular shape to a shape similar to that shown in Figure 5. In Figure 5 this screen is shown to be quadrilateral, with each side arcuate, and joined at their edges to the periphery of the basket so that at a point midway between the 20 rivets this screen is at its greatest distance from the walls of the basket.

For operating the clutch sleeve and the clutch plate there is provided a clutch yoke 119 in the form of a lever pivoted at 120 to the lower end of 25 the arm 87. This lever has extending upwardly therefrom adjacent the arm 87, an arm 121, which has in its upper end a seat for a spring 122, which bears against one side of the arm 87 and tends to prevent rattling in the clutch yoke and to force 30 the arm 121 away from the arm 87 so that the forked end of the lever is moved upwardly, thereby tending to hold the clutch disc 102 in engagement with the lower surface of the pulley 103. 35 It is the lower surface of this pulley which serves as a second clutch member.

To the end of the lever opposite the yoke there is attached a clutch latch 123 by means of a link 124 connected at one end to the clutch latch and at the other end to the lever by means of a bolt 40 125. On the upper end of the clutch latch there is a knob 126 for manipulating the latch. In one side of the latch there is a notch 127. This latch 123 is located in a hole in the chassis or base. Since the base is formed of sheet metal, when 45 the latch is raised to a position so that the notch is opposite the edge of the hole the latch may be made to engage the base by moving the latch so that the base will fit in the notch.

50 Suitably supported on the bottom of the base or chassis is a motor 128, which has the usual motor shaft 129. On this shaft is a pulley 130. In order to properly support the motor in relation to the other parts of the operating mechanism, it has a plate 131 suitably attached thereto, which is supported on opposite sides by means of brackets 132 provided with slides to receive the edges of the plate. In order to deaden any noise and securely and yieldingly hold the motor 55 on the brackets there are provided rubber strips 133 between the plate and the brackets.

60 The pump is provided with a rotor 134, which has upwardly extending therefrom the usual pump shaft 135, provided at its upper end with a 65 pulley 136. Passing around all of the pulleys is a belt 137. This belt may be tensioned by adjusting the motor in its bracket supports, and for the purpose of holding the motor in position and cause the belt to be in a condition of tension, a 70 spring 138 is attached at one end to some suitable part of the motor or the plate, while its other end is attached to the chassis on a flange extending downwardly therefrom.

75 The operating mechanism for the agitator is

located within the housing and is operated by means of the large pulley 54 driven by the motor through the belt. This belt, driven by the motor, also drives the pulley for rotating the spinner. 5 This same belt also engages the pulley for operating the pump. This eliminates the necessity for a large gear box and materially reduces the cost and the weight of the machine.

One of the features of advantage in the present washing machine is the nature of the bearings. The bearings are composed of a fibrous material, and around these bearings, or most of them, and associated with the rotating parts, are oil chambers or cavities. The oil in these cavities 10 will ooze through or pass through the porous bearings into contact with all of the rotating elements. This will occur particularly after the lubricant becomes thin on account of warmth. This thinning and heating of the lubricant will cause it to 15 expand and pass more readily through the porous bearings. After the machine has stopped the lubricant becomes cool, thereby contracting. This contraction will tend to create a vacuum in the lubricant chambers, thereby withdrawing 20 the lubricant from the porous bearings so that the lubricant, substantially as a whole, is retained during the period of inoperation within the lubricant chambers.

By means of the clutch mechanism the washer

may be operated independent of the spinner and the spinner may be operated independent of the agitator.

It is desired to comprehend within this invention such modifications as may be embraced within the claims and the scope of the invention. 5

Having thus fully described the invention, what is claimed as new and desired to be secured by Letters Patent, is:

1. In a washing machine, a tank, a shaft extending into the tank, and a spinner unit supported by the shaft in the tank, said spinner unit consisting of a basket having a perforated bottom and imperforate side walls that converge upwardly, and a screen of the same general shape 15 as the basket but less in size supported at its upper edge by the edge of the basket and having its lower edge attached to the basket at spaced points.

2. In a washing machine, a spinner unit comprising 20 a rotatable basket and a screen in the basket of the same shape but of less diameter than the basket, said screen having around its lower edge a clamp member attached to the basket at spaced points, whereby the lower end of 25 the screen is distorted and drawn out of its true shape.

ROBERT J. WATERWORTH.
